POLISHING BRUSH

Filed July 2, 1924

UNITED STATES PATENT OFFICE.

PATRICK JOSEPH DEVER, OF FREELAND, PENNSYLVANIA.

POLISHING BRUSH.

Application filed July 2, 1924. Serial No. 723,783.

To all whom it may concern:

Be it known that I, PATRICK J. DEVER, a citizen of the United States, residing at Freeland, in the county of Luzerne and 5 State of Pennsylvania, have invented a new and useful Polishing Brush, of which the following is a specification.

The present invention relates to polishing and cleaning brushes and more particularly 10 a brush of the fountain-type.

The primary object of the invention is to provide a brush of this character having means whereby a quantity of cleaning and 15 polishing fluid may be readily and easily taken into the flexible reservoir or bulb forming a part of the brush.

Another important object of the invention is to provide means whereby the flow 20 of the fluid from the reservoir may be regulated at the will of the operator.

With the foregoing and other objects in view which will appear as the description proceeds, the invention resides in the combination and arrangement of parts and in 25 the details of construction hereinafter described and claimed, it being understood that changes in the precise embodiment of the invention herein disclosed, may be made within the scope of what is claimed, without departing from the spirit of the invention. 30

Referring to the drawing:

Figure 1 is an elevational view of a brush constructed in accordance with the invention.

Figure 2 is an enlarged sectional view of the dauber, forming a part of the brush, taken on line 2—2 of Figure 3.

Figure 3 is a sectional view taken on line 3—3 of Figure 2.

Referring to the drawing in detail, the device embodies a hollow handle portion 5 through which the tube 6 extends, the tube supporting the bulb 7, whereby fluid may be drawn into the bulb or reservoir 7 and into 45 the tube 6.

At the outer end of the tube 6 is a flexible tube 8 which has its free end tapered to fit within the opening 9 of the head 10 forming a part of the dauber.

This dauber is formed with a curved surface 10 adapted to receive the felt daubing member 11 which may be secured within the head, in any suitable and well known manner.

As shown, the opening 9 establishes communication between the tube 8 and the dauber so that the cleaning or polishing fluid may find its way to the dauber or felt 11 when it is desired to apply the same to a stove or article being cleaned. 55

Secured to the head 10 is a spring member 12 bent upon itself to provide a pair of arms 13, one of said arms being anchored to the head by means of the screw 14, while the opposite arm is free to move towards 60 and away from the opposed arm.

The dauber head is supported by the rod 15 that is secured to the tubular member 6 one end of the rod 15 being frictionally held within an opening in the head 10 as 70 clearly shown by Figure 2 of the drawing. Forming a part of the rod 15 is a cam 16 that lies adjacent to the free arm of the member 12 so that when the head 10 is rotated, the cam will contact with the free 75 arm of the member 12, forcing the arms towards each other and compressing the flexible tube 8, positioned between the arms.

Thus it will be seen that by moving the head 10, the quantity of fluid passing 80 through the tube 8 may be regulated at the will of the operator. It might be further stated that due to the construction of the member 12, the free end of the tube 8 may be secured to the head 10, in a way to 85 eliminate any possibility of the same becoming accidentally displaced.

Secured to the tube 6 and extending laterally therefrom, is a rod 17 that carries the 90 polishing member 18, which is also in the form of a head and a felt polishing element 19.

In the use of the device, the tubular member 8 is removed from its position within the head 10 and inserted in a suitable container, whereupon the bulb 7 is compressed. The bulb is now released by the operator, creating a suction through the tube 6 drawing the fluid into the reservoir or bulb 7. 95

The tube 8 is now positioned in the opening 9 of the head 10 and the head rotated until the desired quantity of fluid may pass from the tube 8, whereupon the bulb may be compressed slightly to cause liquid to 100 flow to the dauber.

After a suitable coating of fluid has been applied, the device is turned in the hand of the operator to bring the polishing mem- 105

ber into play, whereupon the polishing of the stove may be completed.

I claim:

1. In a device of the character described, a handle, a tube extending through the handle and carrying a bulb on one end thereof, a dauber supported adjacent the other end of the tube, a flexible tube positioned on the first mentioned tube, the free end of the flexible tube being positioned in the dauber, a spring member adapted to embrace a portion of the tube to compress the same, and means disposed adjacent to the dauber for contacting with the spring member when the dauber is rotated.
2. In a device of the character described, a handle, a tube extending through the handle, a rod secured to the tube and extending laterally therefrom, a dauber mounted for rotation on one end of the rod, a flexible tube carried at one end of the first

- 20

mentioned tube and extending into the dauber, a cam carried by the rod, means embracing a portion of the flexible tube and lying in the path of travel of the cam for compressing the flexible tube when the dauber is rotated.

3. In a device of the character described, a handle, a tube extending through the handle, a rod at one end of the tube, a dauber mounted for rotation on the rod, a flexible tube providing communication between the dauber and first mentioned tube, and means controlled by the rotation of the dauber for compressing the flexible tube.

In testimony that I claim the foregoing as my own, I have hereto affixed my signature in the presence of two witnesses.

PATRICK JOSEPH DEVER.
